UNITED STATES PATENT OFFICE.

DAVID L. MEKEEL, OF BEN AVON, PENNSYLVANIA, ASSIGNOR OF ONE-TENTH TO LUTHER K. YODER, OF PITTSBURG, PENNSYLVANIA.

PIT-FURNACE-COVER-OPERATING MECHANISM.

No. 892,865.

Specification of Letters Patent.

Patented July 7, 1908.

Application filed January 25, 1907. Serial No. 353,953.

To all whom it may concern:

Be it known that I, DAVID L. MEKEEL, a resident of Ben Avon, in the county of Allegheny and State of Pennsylvania, have invented a new and useful Improvement in Pit-Furnace-Cover-Operating Mechanism; and I do hereby declare the following to be a full, clear, and exact description thereof.

My invention relates to mechanism for operating the covers of pit-furnaces, and it has for its object to provide a cheap, simple, and efficient mechanism for moving such cover to and from the opening of the furnace, said mechanism being under easy and perfect control at all times.

I shall now describe my invention so that others skilled in the art may manufacture and use the same, reference being had to the accompanying drawing, in which

Figure 1 is a plan view showing a portion of a set of pit-furnace covers provided with my invention. Fig. 2 is a vertical section on the line 2—2 of Fig. 1. Fig. 3 is a like view, showing another manner of mounting the cover. Fig. 4 is a detail view.

Like symbols of reference indicate like parts in each of the several figures.

In the drawing, 1 represents the ordinary form of pit-furnace for heating ingots, having the usual opening 2, over which opening is the ordinary cover 3. This cover 3 is mounted in suitable frame-work 4 and rests upon the walls 5.

Mounted upon the top of the furnace and traveling upon the rails 6 by the wheels 7, is a carriage 8 for moving the cover 3, which is what is known as the "gun carriage", said carriage being provided with the forwardly and rearwardly extending frames 9 and 10. The forward frame 9 is loosely connected to the cover 3 at its center and side, as at 11 and 11', in the usual manner, and the rear frame 10 has wheels 12 at its end for engaging with and traveling in a track 13, whereby the cover 3 is raised and lowered through said wheels engaging and disengaging suitable devices (not shown) in the usual manner.

Mounted on a stand or platform 14, is an electric motor 15, which is of any ordinary approved type having a gear-wheel 16 mounted on its armature shaft 17, adapted to mesh with a gear-wheel 18 on one end of a shaft 19. The shaft 19 is mounted in suitable bearings 20 extending out from the motor 15 and on the platform 14, while its oppo-

site end is provided with a pinion 21, which is adapted to engage with a rack 22 fitting over said pinion and held in engagement therewith by a bracket 22' extending from the top of the bearing frame 20, while said rack 22 is also pivoted at its front end to the forward frame 9 of the carriage 8.

The operation of my improved mechanism is as follows:—When it is desired to remove the cover 3 from the opening 2, the motor 15 is started, which causes the shaft 19 to be revolved through the gear-wheels 16 and 18 on said shaft and armature shaft respectively, which will revolve the shaft 19 and the pinion 21 thereon and draw back the rack 22 engaging therewith. When the rack 22 begins to move, the cover 3 will be slightly raised by the wheels 12 of the carriage 8, and the continued movement of the rack will draw the cover back to the position shown by dotted lines in Fig. 2. When it is desired to replace the cover in position, the motor is reversed, which will cause the parts to be returned to their initial position.

If desired, the cover 3 can be mounted on overhead tracks 24 by means of the wheels 23, as shown in Fig. 3, in which case the rack 22 can be connected directly with the side frame 4 of the cover and the cover can then be moved or slid laterally along a platform or frame 25 on top of the furnace in its forward and backward movement.

Various other modifications and changes in the design, construction and operation of my improved pit-furnace-cover operating device may be resorted to without departing from the spirit of the invention or sacrificing any of its advantages. It will thus be seen that the operating parts for moving the cover will be away from the heat around the opening to the furnace, which will insure a positive and direct movement of the cover at all times, while any jerky movement or strain on the cover or parts is reduced to a minimum, lessening thus the liability to breakage and getting out of order of the parts.

I claim:—

1. In combination, a pit-furnace cover, mechanism directly connected thereto for moving the same, an electric motor, and mechanism directly connected to said cover-operating mechanism and to the armature shaft of said motor, substantially as described.

2. In combination, a pit-furnace cover, a rack directly connected thereto for moving the same, an electric motor, and mechanism directly connected to said rack and to the armature shaft of said motor, substantially as described.

3. In combination, a pit-furnace cover, a rack connected thereto for moving the same, a shaft, a gear-wheel on said shaft meshing with said rack, an electric motor, and a gear-wheel mounted on the armature shaft of said motor and engaging a second gear-wheel on said first-named shaft; substantially as described.

4. In combination, a pit-furnace cover, mechanism directly connected thereto for

moving the same, an electric motor; and mechanism operated by said electric motor for actuating said cover-moving mechanism, substantially as described. 20

5. In combination, a pit-furnace cover, a rack connected thereto for moving the same, a pinion for moving the rack, mechanism for holding said rack in engagement with said pinion, and an electric motor for opening said pinion, substantially as described. 25

In testimony whereof, I the said DAVID L. MEKEEL have hereunto set my hand.

DAVID L. MEKEEL.

Witnesses:

J. N. COOKE,
JAMES L. WEHN.

Correction in Letters Patent No. 892,865.

It is hereby certified that in Letters Patent No. 892,865, granted July 7, 1908, upon the application of David L. Mekeel, of Ben Avon, Pennsylvania, for an improvement in "Pit-Furnace-Cover-Operating Mechanism," an error appears in the printed specification requiring correction, as follows: In line 25, page 2, the word "opening" should read *operating*; and that the said Letters Patent should be read with this correction therein that the same may conform to the record of the case in the Patent Office.

Signed and sealed this 28th day of July, A. D., 1908.

[SEAL.]

E. B. MOORE,
Commissioner of Patents.

2. In combination, a pit-furnace cover, a rack directly connected thereto for moving the same, an electric motor, and mechanism directly connected to said rack and to the armature shaft of said motor, substantially as described.

3. In combination, a pit-furnace cover, a rack connected thereto for moving the same, a shaft, a gear-wheel on said shaft meshing with said rack, an electric motor, and a gear-wheel mounted on the armature shaft of said motor and engaging a second gear-wheel on said first-named shaft; substantially as described.

4. In combination, a pit-furnace cover, mechanism directly connected thereto for

moving the same, an electric motor; and mechanism operated by said electric motor for actuating said cover-moving mechanism, substantially as described. 20

5. In combination, a pit-furnace cover, a rack connected thereto for moving the same, a pinion for moving the rack, mechanism for holding said rack in engagement with said pinion, and an electric motor for opening said pinion, substantially as described. 25

In testimony whereof, I the said DAVID L. MEKEEL have hereunto set my hand.

DAVID L. MEKEEL.
